UNITED STATES PATENT OFFICE.

AUGUST HOTHAN, OF BROOKLYN, NEW YORK, ASSIGNOR TO THE JOHN KRODER & HENRY REUBEL CO., OF NEW YORK, N. Y.

CURTAIN-POLE RING.

SPECIFICATION forming part of Letters Patent No. 695,313, dated March 11, 1902.

Application filed October 19, 1901. Serial No. 79,234. (No model.)

To all whom it may concern:

Be it known that I, AUGUST HOTHAN, a citizen of the United States, and a resident of the city of New York, borough of Brooklyn, in the 5 county of Kings and State of New York, have invented a new and Improved Curtain-Pole Ring, of which the following is a full, clear, and exact description.

The invention relates to curtain-pole rings 10 having rollers traveling on the pole; and the object of the invention is to provide a new and improved curtain-pole ring which is simple and durable in construction, cheap to manufacture, and arranged to securely hold 15 the roller-bearings in position in the ring and to insure a free rotation of the roller at all times in the bearings.

The invention consists of novel features and parts and combinations of the same, as 20 will be fully described hereinafter and then pointed out in the claims.

A practical embodiment of the invention 25 is represented in the accompanying drawings, forming a part of this specification, in which similar characters of reference indicate corresponding parts in all the views.

Figure 1 is a side elevation of the pole-ring 30 as applied to a curtain-pole, the latter being shown in cross-section. Fig. 2 is a transverse section of the improvement on the line 22 of Fig. 1. Fig. 3 is an enlarged sectional side elevation of the improvement. Fig. 4 is a perspective view of one of the rollers and its bearing, and Fig. 5 is an inside view of 35 part of the ring.

The curtain-pole ring A for the pole B is preferably of split tubular form and carries at its lower end a ring C for supporting the curtain in the usual manner. One or more 40 roller-bearings are arranged on the inside of the ring, each roller-bearing having a roller D, adapted to travel on the pole B and extending into a recess A', formed transversely on the inside of the ring, as plainly shown in 45 the drawings, particular reference being had to Fig. 5. The bearing E for each roller B is preferably made of spring-wire and is formed with a middle or axle portion E' for the roller D to turn on, and from the ends of the said 50 axle portion extend integrally the U-shaped ends for engagement with the ring to securely

hold the bearing in place on the ring. The inner members E² of the U-shaped ends fit into slots A², formed in the ring and leading to the recess A' at opposite sides thereof, and the outer members E³ of the bearing fit into apertures A³, formed in the ring at the sides of the slots A², as plainly shown in Fig. 5. Each outer member E³ of the bearing is formed with a notch E⁴, adapted to engage 60 the wall of the aperture A³, so that when the members E³ are sprung into position in the apertures A³ the said notches engage the walls to securely lock the bearing against accidental displacement from the ring A. The 65 middle portion E⁵ of each of the U-shaped ends of the bearing is adapted to abut against that portion of the ring lying between the corresponding aperture A³ and slot A², so that the bearing is prevented from moving in an outward direction on the ring when pressure is applied on the ring C in a downward direction by the weight of the curtain.

From the foregoing it is evident that by 70 having the notches E⁴ engage the ring as described the bearing is not liable to drop accidentally out of the ring when the latter is not in use on the curtain-pole and by having the middle portions E⁵ of the bearing limit the inward movement of the bearing, 80 the latter is prevented from rubbing against the walls of the recess A'. By having the members E² E³ of each bearing end engage the ring as described the bearing is held securely against a transverse rocking movement, and consequently the rings hang properly in a vertical position on the curtain-pole 85 B at all times.

Having thus described my invention, I claim as new and desire to secure by Letters 90 Patent—

1. A curtain-pole ring, comprising a ring having a recess at the inside, slots leading into the recess at opposite sides, and apertures at the sides of the slots, a roller extending into the recess, and a bearing having an axle portion for the roller to turn on, and U-shaped ends integral with the axle portion; the inner members of the said ends engaging the slots, and the outer members engaging 95 the said apertures, as set forth.

2. A curtain-pole ring, comprising a ring

having a recess at the inside, slots leading into the recess at opposite sides, and apertures at the sides of the slots, a roller extending into the recess, and a bearing having an 5 axle portion for the roller to turn on, and U-shaped ends integral with the axle portion; the inner members of the said ends engaging the slots, and the outer members engaging the said apertures, the said outer members 10 having notches engaging the walls of the said apertures, as set forth.

3. In a curtain-pole ring, a roller-bearing having an axle portion and the U-shaped end portions disposed in close relation to each 15 other, and a roller mounted on said axle portion and between said end portions, whereby the U-shaped portions limit the lateral play of the roller on the axle.

4. A slotted curtain-pole ring provided with apertures, a roller-bearing having yieldable 20 retaining end portions on opposite sides of an axle portion and snapped into engagement with said perforated ring, and a roller mounted on the axle portion and projecting into the slot of said ring, said bearing being provided 25 on opposite sides of the axle portion with means for confining said roller against lateral play on said axle portion.

In testimony whereof I have signed my name to this specification in the presence of 30 two subscribing witnesses.

AUGUST HOTHAN.
